LOOM

John O. Hunt, Greenville, S. C., assignor to Ware Shoals Manufacturing Co., Ware Shoals, S. C., a corporation of South Carolina

Original application March 31, 1943, Serial No. 481,247. Divided and this application June 26, 1943, Serial No. 492,387

11 Claims. (Cl. 139—79)

This invention relates to looms in which heddle frames are raised and lowered to produce warp sheds by means of a shedding motion which includes treadles connected to the frames, and is concerned, more particularly, with a novel shedding mechanism for such looms, by the use of which the weave of the fabric being produced may be varied at intervals. The loom of the invention may be employed in the production of fabrics made up of recurring weaves or various kinds and, for purposes of explanation, a form of the new loom suitable for the weaving of a fabric consisting of alternating lengths of plain and tubular goods will be illustrated and described in detail. It is to be understood, however, and will be apparent that the utility of the invention is not limited to the production of that specific fabric.

Heretofore various looms capable of weaving alternate sections of goods of different weave, and sometimes referred to as bag looms, have been proposed and some of those looms have been put into practical use. The commercial bag looms with which I am familiar have the limitation that they cannot be readily adjusted to produce small variations in the lengths of the different sections of the fabric and, therefore, practical considerations restrict the variety of their output. Other looms proposed have apparently not gone into use because of such objectionable features as poor mechanical construction which would result in their being frequently shut down for repair and adjustment.

The present invention is, accordingly, directed to the provision of a loom for the production of a fabric made up of alternate sections of different weave and is superior to prior looms in that it is of simple rugged construction so that it may be operated for long periods without interruption for repairs. The shedding motion employed is easy to maintain in working condition and it is operated wholly by mechanical means and may be controlled by various pattern devices. I prefer to use that disclosed in my pending application Serial No. 481,247, filed March 31, 1943, of which the present application is a division.

A loom constructed in accordance with the principles of the invention includes a plurality of heddle frames, for example, four, and a treadle connected to each of the frames. Two of the treadles are provided with individual actuating cams by which the treadles are raised and lowered and one of these treadles is pro-

vided with means by which the two treadles can be connected together so as to be raised and lowered in unison by both the cams. The remaining two treadles are not actuated directly but associated therewith are three levers, each of which has an actuating cam. Means are provided by which the treadles of the second pair can be connected individually to two of the three levers to be raised and lowered therewith or both treadles can be connected to the third lever. The means by which the treadles of the first pair are connected together and by which the treadles of the second pair are connected to separate levers or to the same lever are actuated by means under the control of a pattern device.

For a better understanding of the invention, reference may be had to the accompanying drawings in which

20 Fig. 1 is a sectional view of the treadle mechanism on the line 1—1 of Fig. 2;

Fig. 2 is a sectional view on the line 2—2 of Fig. 1;

25 Figs. 3 and 4 are sectional views on the line 3—3 and 4—4, respectively, of Fig. 2;

Figs. 5 and 6 are elevational views of cams used in that part of the apparatus shown in Fig. 3;

30 Fig. 7 is a sectional view on the line 7—7 of Fig. 2; and

Figs. 8 to 13, inclusive, are views in side elevation of the treadles, levers, and associated operating parts.

35 The loom illustrated in the drawings includes four heddle frames, not shown, connected in the usual way to treadles 21, 22, 23, and 24, which are mounted for swinging movement on a rod 25 supported on a suitable part of the loom structure. Treadle 21 is provided with a roller 26 mounted at the top of a box 21 in position to be engaged by a cam on the loom cam shaft and the treadle also carries a pair of plates 28 attached to its opposite faces and extending downward, the plates having slots 29 extending lengthwise of the treadle. The hub 30 of the treadle is provided with a depending bracket 31 through which extends a rod 32 and the rod is provided with a pin 33 which extends through the slots 29 in plates 28. The pin is provided with rollers engaging the walls of the slots and the pin extends outwardly past plate 28 on the side toward treadle 22 and carries a roller 34 on its exposed end.

50 Treadle 22 is provided with a box containing

a roller 35 engageable by a cam on the cam shaft and the box is formed with an extension 36 having a recess 36a so placed that, when rod 32 on treadle 21 is moved to its inner position toward the hub of the treadle, roller 34 on pin 33 will lie within the recess. When the parts are in this position, the treadles 21 and 22 are connected together by the pin and are operated as a unit by the cams acting on rollers 26 and 35. When rod 32 and pin 33 are in their outer positions, roller 34 on the pin is outside the recess 36a and the treadles are operated by their individual cams.

Lying between treadles 22 and 23 is a lever 37 pivotally mounted at one end on rod 25 and provided with a box containing a roller 38 engageable by a cam on the cam shaft. Beyond the box, the lever has an extension 39 in which is formed a vertical slot 40. The treadle 23 is not equipped with a cam roller but is provided with a pair of depending plates 41 having lengthwise slots 42. At its hub, treadle 23 is provided with a bracket 43, through which extends a rod 44 having a pin 45 extending through slots 42 in plates 41 and having rollers running on the walls of the slots. The pin 45 projects outwardly beyond both plates and it is provided with rollers 46 at its ends. When rod 44 is moved outwardly so that pin 45 lies at the outer ends of slots 42, the roller 46 at one end of the pin lies beneath the extension 39 on lever 37 as shown in Fig. 2, so that treadle 23 will be raised and lowered with lever 37 as the latter is operated by its cam.

Between treadles 23 and 24 is a lever 47 provided with a box 48, in which is mounted a roller 49 engageable by a cam on the cam shaft. The outer end of the box terminates in an extension 50 and, when pin 45 on rod 44 on treadle 23 is at the outer end of slots 42, one of the rollers 46 at the end of the pin lies outward beyond extension 50, while the roller at the other end of the pin lies beneath extension 39 on lever 37. When the rod 44 is moved inward, one roller 46 on the pin lies beneath extension 50 while the roller 46 at the other end of the pin is aligned with the slot 40 in extension 39 on lever 37. Thus, as rod 44 is moved in or out, pin 45 serves to connect treadle 23 either to lever 37 or to lever 47 to be actuated therewith.

Treadle 24 is of the same construction as treadle 23 in that it has no roller engageable by a cam but is provided with a rod 44a similar to rod 44 and with a pin having rollers lying within slots in plates depending from the treadle and also having rollers 51 at its ends outside the plates. When the pin on treadle 24 is in its outer position, the roller 51 at one end lies beyond extension 50 on lever 47 and treadle 24 is independent of lever 47. When the pin is at the other end of the slot, one of the rollers 51 on the pin lies beneath extension 50 so that treadle 24 is then connected to lever 47 to be actuated therewith.

Next to treadle 24 is a lever 52 provided with a box 53 having a roller 54 engageable by a cam on the cam shaft, the box terminating in extension 55 provided with a vertical slot 56. When the pin on treadle 24 is in its outer position, one of the rollers 51 on the end of the pin lies beneath the extension 55 on lever 52 so that treadle 24 and lever 52 are actuated together. When the pin on treadle 24 lies in its inner position, the roller 51 on the end of the pin is in registry with the slot 56 on lever 52 and, at the

same time, the roller 51 at the other end of the pin lies beneath extension 50 on lever 47. The arrangement is such, therefore, that, when the pin on treadle 24 is in one position, the treadle is connected to lever 47 to be actuated therewith; when the pin is in its other position, the treadle is connected to lever 52.

The rod 32 on lever 21 is connected to an arm 57 fast on a tubular shaft 58 mounted in appropriate brackets on the loom frame. Within shaft 58 is a shaft 59 extending beyond the end of shaft 58 and provided with a pair of arms 60, 60a which are connected, respectively, to rods 44 and 44a on treadles 23 and 24. The position of rod 32 is thus determined by the angular position of shaft 58 and rods 44 and 44a move in unison and their positions are determined by the angular position of shaft 59. As the positions of rods 32, 60, and 60a determine whether or not treadles 21 and 22 operate independently or are connected together and whether treadles 23 and 24 are connected to their respective levers 37 and 52 or both are connected to lever 47, it will be apparent that the action of the treadles and levers are controllable by the shifting of shafts 58 and 59 to different angular positions.

The cams for actuating the treadles and levers are mounted on a shaft 61 which extends over the tops of the rollers on the treadles and levers. 30 Cam 61a acting on roller 26 on treadle 21 and cam 62 acting on roller 35 of treadle 22 are alike but are so mounted on shaft 61 as to be 180° out of phase. Cam shaft 61 makes one revolution for each four picks woven into the fabric and cams 61a and 62 are of such form that, as the cam shaft rotates, they depress their respective treadles and thus raise the heddles connected thereto one pick out of four. The heddles connected to treadles 21 and 22 may thus be considered to be up for one pick and down for three picks in each cycle of four picks. When treadles 21 and 22 are connected together by pin 33 controlled by rod 32, cams 61 and 62 both operate on both treadles, and the treadles are up and down for alternate picks.

Cam 63 acting on roller 38 of lever 37 has such a shape that the lever is down for three picks and up for one in each cycle of four picks and cam 64 acting on roller 54 of lever 52 has the same shape as cam 63 but is 180° out of phase therewith. Cam 65 acting on roller 49 of lever 47 has a shape such that the lever is alternately up and down for successive picks. When rods 44 and 44a on treadles 23 and 24 are shifted simultaneously by rocking shaft 50 to their outer positions, so that treadle 23 is connected to lever 37 and treadle 24 is connected to lever 52, the treadles are down for three picks and up for one out of each cycle of four picks and are out of step 180°. When rods 44 and 44a are moved to their inner positions, treadles 23 and 24 are both connected to lever 47 and are alternately up and down for successive picks.

In the weaving of tubular fabric, treadles 21 and 22 are disconnected and treadles 23 and 24 are connected, respectively, to levers 37 and 52. With this arrangement, three sets of warp threads are disposed at one side of each shed and one set at the other side and the loom produces two fabrics connected at the selvages to form a tube. When levers 21 and 22 are connected together and treadles 23 and 24 are both connected to lever 47, each shed contains two sets of warp threads at each side and the fabric woven is plain goods.

The changeover from one type of weaving operation to the other is effected by the rocking of shafts 58 and 59 by means of a pair of cams 66, 67 which are connected together but loose upon a shaft 68, which is suitably supported on a loom frame and driven through gearing 69 from the main drive shaft of the loom. A ratchet wheel 70 is mounted loosely on shaft 68 at one side of the cams and is connected to the cams so that, as the ratchet wheel is advanced, the cams are likewise advanced. At the other side of the cams on shaft 68 is a disc 71, which is fast to the cams and loose on the shaft and has peripheral depressions in which may be seated a roller 72 on a spring pressed arm 73. The entrance of the roller into one of the depressions serves to prevent over-running of the ratchet wheel and cams.

The ratchet wheel is advanced by a pawl 74 on a lever 75 pivoted on a suitable part of the loom frame and the lever is provided with a roller 76 held against the surface of a cam 77 fast on shaft 68 by means of a spring 78 acting on the lever. As cam 77 rotates, it advances the pawl two steps per revolution and, in the second step, the pawl, if free to do so, will engage a tooth on the ratchet wheel and advance the wheel and cams 66 and 67 by one step.

The cams control the positions of shafts 58 and 59 and, for this purpose, each shaft is provided with an arm 79 provided with a roller 80 bearing against one of the cams. The shape and arrangement of the cams is such that, on each double step in the movement of the ratchet wheel, each cam shifts its shaft 58 or 59 from one position to the other and a change in the manner of actuation of the treadles is effected. The cams, though similar, are secured together in offset relation so that the rocking of shafts 58 and 59 with accompanying movements of rods 32, 44 and 44a will take place when the treadles and levers are not being depressed by their cams so that the connecting pins on the rods will not undergo strain.

Shaft 68 rotates continuously while the loom is running and lever 75 is depressed by cam 77 once per revolution of the shaft. If pawl 74 were permitted to act each time shaft 75 is depressed, the mode of operation of the loom would continually change and the sections of plain and tubular goods would be extremely short. In order that the sections may be of proper length, the pawl is prevented from acting on the ratchet wheel except at the desired intervals and, for this purpose, the pawl is kept free of the ratchet wheel by a guard 81 formed as one end of a lever 82 pivoted on rod 83 supported in any convenient manner, the rod also serving as a pivot for arm 73. The other end of lever 82 is connected by a link 84 to a pattern mechanism of suitable form, such as that illustrated in my co-pending application Serial No. 481,247, filed March 31, 1943. Under the control of the pattern mechanism, the lever 82 is swung to render guard 81 operative or inoperative, as the pattern may determine, and when the guard is inoperative, the pawl 74 is effective to advance cams 66 and 67 by one step so as to change the manner of actuation of the treadles.

In the operation of the apparatus, the treadles and their associated heddle frames are raised and lowered to produce the sheds and the number of sets of warp threads in the two sides of each shed depends upon the manner in which the treadles are actuated; that is, on whether treadles 21 and 22 are connected together or disconnected

and on whether treadles 23 and 24 are connected to their respective levers 37 and 52 or both are connected to lever 41. The changeover in the operation of the treadles occurs whenever cams 66 and 67 are advanced and such advance is controlled by the pattern device. By varying the action of the device, the loom can be controlled so as to weave alternating sections of tubular and plain goods with the sections of varying lengths, as determined by the setup of the pattern device. The changeover in the treadle action is effected wholly by mechanical means and, as the changeover occurs at the proper instants in the loom operation so that no strains are imposed on the connecting pins, the mechanism is not subject to damage and can be run for long periods of time without requiring repair or adjustment.

I claim:

1. In a loom, the combination of a pair of treadles adapted to be connected to heddle frames, cams for lowering the individual treadles, means for connecting the treadles together to be lowered in unison by the action of both cams, a second pair of treadles adapted to be connected to heddle frames, a pair of levers, cams for lowering the individual levers, means for connecting the levers to respective treadles of the second pair, a third lever, a cam for lowering the third lever, means for connecting the third lever to both treadles of the second pair, and means for operating the several connecting means.
2. In a loom, the combination of a pair of treadles adapted to be connected to heddle frames, cams for lowering the individual treadles, means for connecting the treadles together to be lowered in unison by the action of both cams, a second pair of treadles adapted to be connected to heddle frames, three levers, cams for lowering the individual levers, means operable in alternation to connect the treadles of the second pair respectively to two of the levers and to connect both said treadles simultaneously to the third lever, and individual means for operating the connecting means associated with the two pairs of treadles.
3. In a loom, the combination of a pair of treadles adapted to be connected to heddle frames, cams for lowering the individual treadles, means on one of the treadles operable to connect the treadles together to be lowered in unison by both the cams, a second pair of treadles adapted to be connected to heddle frames, three levers, cams for lowering the individual levers, means operable alternatively to connect the individual treadles of the second pair, respectively, to two of the levers to be lowered therewith and to connect both treadles of the second pair to the third lever to be lowered in unison therewith, and separate means for controlling the action of the connecting means.
4. In a loom, the combination of a pair of treadles adapted to be connected to heddle frames, cams for lowering the individual treadles, means on one of the treadles operable to connect the treadles together to be lowered in unison by both the cams, a second pair of treadles adapted to be connected to heddle frames, three levers, cams for lowering the individual levers, means on the respective treadles of the second pair for alternatively connecting said treadles, respectively, to two of the levers to be lowered therewith and connecting said treadles to the third lever to be lowered in unison therewith, and separate means for controlling the action of the connecting means.

5. In a loom, the combination of a pair of treadles adapted to be connected to heddle frames, cams for lowering the individual treadles, means for connecting the treadles together to be lowered in unison by the action of both cams, a second pair of treadles adapted to be connected to heddle frames, three levers, cams for lowering the respective levers, a member carried by each of the treadles of the second pair, said members being movable between different positions, in one of which the members connect their treadles, respectively, to two different levers to be lowered therewith, and in the other of which the members connect their treadles to the third lever to be lowered in unison therewith, and means for moving the three members.

6. In a loom, the combination of a pair of treadles adapted to be connected to heddle frames, cams for lowering the individual treadles, a member on one of the treadles movable to and from a position in which it connects the treadles together to be lowered in unison by both cams, means for moving said member to and from said position, a second pair of treadles adapted to be connected to heddle frames, three levers, cams for lowering the respective levers, a member carried by each of the treadles of the second pair, said members being movable between different positions, in one of which the members connect their treadles, respectively, to two different levers to be lowered therewith, and in the other of which the members connect their treadles to the third lever to be lowered in unison therewith, and means for moving the members associated with the treadles of the second pair.

7. In a loom, the combination of a pair of treadles adapted to be connected to heddle frames, cams for lowering the individual treadles, a member on one of the treadles movable to and from a position in which it connects the treadles together to be lowered in unison by both cams, a rod attached to said member for moving it, a second pair of treadles adapted to be connected to heddle frames, three levers, cams for lowering the respective levers, a member carried by each of the treadles of the second pair, said members being movable between different positions, in one of which the members connect their treadles, respectively, to two different levers to be lowered therewith, and in the other of which the members connect their treadles to the third lever to be lowered in unison therewith, a pair of rods connected respectively to the members on the treadles of the second pair, and separate means for moving the first rod and the pair of rods.

8. In a loom, the combination of a pair of treadles adapted to be connected to heddle frames, cams for lowering the individual treadles, means for connecting the treadles together to be lowered in unison by the action of both cams, a second pair of treadles adapted to be connected to heddle frames, a pair of levers, cams for

lowering the individual levers, means for connecting the levers to respective treadles of the second pair, a third lever, a cam for lowering the third lever, means for connecting the third lever to both treadles of the second pair, and means under control of a pattern for operating the several connecting means.

9. In a loom, the combination of a pair of treadles adapted to be connected to heddle frames, 10 cams for lowering the individual treadles, means for connecting the treadles together to be lowered in unison by the action of both cams, a second pair of treadles adapted to be connected to heddle frames, a pair of levers, cams for lowering the individual levers, means for connecting the levers to respective treadles of the second pair, a third lever, a cam for lowering the third lever, means for connecting the third lever to both treadles of the second pair, means for operating the several connecting means, including a pair of cams, and pattern-controlled means for rotating the cams.

10. In a loom, the combination of a pair of treadles adapted to be connected to heddle frames, cams for lowering the individual treadles, 25 means for connecting the treadles together to be lowered in unison by the action of both cams, a second pair of treadles adapted to be connected to heddle frames, a pair of levers, cams for lowering the individual levers, means for connecting the levers to respective treadles of the second pair, a third lever, a cam for lowering the third lever, means for connecting the third lever to both treadles of the second pair, means for operating the several connecting means, including a pair of cams, pawl and ratchet means for rotating the cams stepwise, and pattern-controlled means for controlling the action of the pawl on the ratchet.

11. In a loom, the combination of a pair of treadles adapted to be connected to heddle frames, cams for lowering the individual treadles, 40 a member on one of the treadles movable to and from a position in which it connects the treadles together to be lowered in unison by both cams, a rod attached to said member for moving it, a second pair of treadles adapted to be connected to heddle frames, three levers, cams for lowering the respective levers, a member carried by each of the treadles of the second pair, said members 45 being movable between different positions, in one of which the members connect their treadles, respectively, to two different levers to be lowered therewith, and in the other of which the members connect their treadles to the third lever to be lowered in unison therewith, a pair of rods connected, respectively, to the members on the treadles of the second pair, a shaft connected to the first rod, a second shaft connected to the pair of rods, cams for determining the angular positions of the respective shafts, and pattern-controlled means for rotating the cams.

JOHN O. HUNT.
